(57) CLAIM

The ornamental design for a planter, as shown.

DESCRIPTION

FIG. 1 is a top perspective view of the planter;

FIG. 2 is a side view thereof;

FIG. 3 is a side view thereof;

FIG. 4 is a side view thereof;

FIG. 5 is a side view thereof;

FIG. 6 is a top plan view thereof; and,

FIG. 7 is a bottom plan view thereof.

The broken lines showing the bottom in FIGS. 6 and 7 are included for the purpose of illustrating portions of the planter that form no part of the claimed design.
